U. S. ALSRUHE

OPERATING MECHANISM FOR SLIDE VALVES

Filed Jan. 22, 1925

UNITED STATES PATENT OFFICE.

URBAN S. ALSRUHE, OF TOWSON, MARYLAND.

OPERATING MECHANISM FOR SLIDE VALVES.

Application filed January 22, 1925. Serial No. 4,124.

To all whom it may concern:

Be it known that I, URBAN S. ALSRUHE, a citizen of the United States, residing at Towson, in the county of Baltimore and State of Maryland, have invented an Operating Mechanism for Slide Valves, of which the following is a full and complete specification.

My invention is an improvement in slide-valve mechanism for engines using steam or compressed air as the motive force, and relates more especially to the means by which the slide-valve is actuated to cooperate with the inlet and outlet ports of the cylinder.

In the operation of the conventional type of engine having a cylinder and slide-valve with mechanism for operating the latter comprising connecting rods and a cam device on a driven shaft the reciprocating motion imparted to the slide-valve admits the fluid pressure gradually into the cylinder with a corresponding exhaust owing to the operation of the usual form of cam, and this interferes to a more or less extent with the effective operation of the power introduced into the cylinder and exhausted therefrom in the operation of the piston.

The principal object of my invention is to provide a particular form of cam device for operating the slide-valve through the intervention of the usual connecting rods, whereby the slide is moved quickly from one position to the other for a more effective intake and exhaust of the steam or fluid pressure so as to insure a more powerful and economical operation of the engine.

A further object of my invention is to provide an operating device for imparting a reciprocating motion to the rods operating the usual form of slide-valve which may be readily substituted for the ordinary form of cam ordinarily used, the operating device in the present instance being not only effective in the operation of the engine but also simple in construction, positive in action, and easily applied.

Other objects and advantages of my invention will hereinafter appear, and what I claim as new and desire to secure by Letters-Patent is more specifically set forth in the appended claims.

In the drawings, forming a part of this specification:—

Fig. 1 is a side elevation illustrating the application of my invention to a conventional type of engine.

Fig. 2 is an enlarged detail view, in side elevation, of the operating mechanism or cam device comprising my invention.

Fig. 3 is a similar view, with the side plate removed and the yoke member partly in section.

Fig. 4 is a vertical sectional view through the operating mechanism or cam device.

I have illustrated my invention as applied to a conventional type of engine comprising a cylinder 10 through one end of which the piston-rod 11 works and is connected to the driving-arm 12 applying the power by means of a slide 13 having a reciprocating movement between guide-rails 14 supported by standards 15; the cylinder being provided as usual with a steam-chest 16 in which the ordinary form of slide-valve (not shown) operates to successively cover and uncover the inlet and exhaust ports leading into the cylinder. This type of engine is also provided with a valve-rod 17 extending through one end of the steam-chest for the operation of the slide-valve, and as usual this rod is actuated from a driven shaft, as 22, by a connecting-rod 20 and cam device on said shaft with a slide 18 supported in guide-rails 19 forming part of the connections. These parts are all common to this type of engine, and therefore further description of the construction and operation of the same is unnecessary, being well understood by those skilled in the art, and are illustrated herein to show one application of my improved form of operating mechanism or cam device.

Furthermore, it will be understood that the application of my improved operating mechanism or cam device, hereinafter particularly described, is not limited in its application to this particular type of engine but may be used in connection with other forms of engines and in other situations where it is desired to impart an intermittent reciprocating motion to a connecting-rod, &c.

In carrying out my invention I provide in the first place a metal wheel 23 having its periphery concentric to its axis or shaft on which it is mounted, and attach to the periphery at the center thereof a single tappet 24 having its working face beveled, as shown, to cooperate with shoulders on the companion member or yoke 25 of the cam device. This yoke-member is mounted on the tappet-wheel being for the purpose pro-

vided internally with an elliptical recess and central openings at its sides to receive said wheel and its driving shaft so that the said yoke may have a limited reciprocating motion, the narrow part of the recess being of approximately the same diameter as the wheel for a proper bearing of the yoke and of course the extent of movement is determined by the length of the elliptical-shaped recess. In order to impart an intermittent reciprocating motion to the yoke-member for a quick movement of the slide-valve, in contradistinction to the slow of gradual movement imparted by the ordinary form of cam, shoulders 27^a 27^b are formed in said yoke-member at opposite sides of the narrow part of the elliptical recess therein, said shoulders being preferably in the form of spring-actuated dogs for the purpose hereinafter explained, and in operation the tappet 24 when the wheel 23 is turned in either direction passes one of the shoulders or dogs and engages the other to move the yoke alternately in opposite directions. To accomplish this the shoulders formed by the spring-actuated dogs are located at opposite sides of the transverse diameter of the elliptical recess, in cavities 28, and are spaced from said diameter respectively so that their tangential movement with respect to the wheel permits the tappet to pass the shoulder or dog at the limit of movement of the yoke-member in the same direction as said tappet, the dog in this instance forming a rigid shoulder by bearing against the wall of recess 28; for instance, when the tappet-wheel is rotating in the direction of the arrow Fig. 3 the tappet 24 engages dogs 27^a successively and moves the yoke-member in opposite directions alternately and in each instance until the tappet passes the dog 27^a—it being understood that it is the tangential movement of the rigid dog carried by the yoke-member that allows the tappet to pass said dog. When the direction of movement or rotation of the driving-shaft and tappet-wheel is reversed the tappet will then in like manner pass by the dogs 27^a without disturbing the same and engage dogs 27^b to impart the required reciprocating motion to the yoke-member. Although rigid shoulders may be used it is preferable to use the spring-actuated dogs to permit the tappet to move one of the dogs out of the way and pass on to the other under certain conditions, as for instance when the yoke-member is by accident or otherwise moved to an intermediate position when the tappet is on a line with the longitudinal diameter of the elliptical recess, then when the tappet-wheel is rotated the tappet would trip the first dog and engage the second to move the yoke-member for a further regular operation of the cam device; that is to say, suppose the tappet to be

at the forward part of the wheel, on a line with the longitudinal center of the elliptical recess and the yoke member should be moved to the left (Fig. 3) a rotation of the tappet-wheel in the direction of the arrow would trip dog 27^b at the lower part of the yoke-member and engage dog 27^a, and, conversely, a reverse rotation of the tappet-wheel would trip spring-actuated dog 27^a at the upper part of the yoke-member and pass on to engage dog 27^b. Of course in the regular operation of the cam device the friction of the parts it operates, as for instance the valve-slide, slide 18 and connecting rods 17 and 20, will hold the yoke member to limit of movement in both directions, but as hereinbefore pointed out a shoulder or member which will yield in one direction is desirable to take care of an emergency such as stated, for if rigid shoulders were provided the tappet would, in the case stated, engage the first shoulder and by moving it towards the transverse diameter of the elliptical recess, or towards the periphery of the tappet-wheel, lock the parts. It will be readily seen, therefore, that in the regular operation of the cam device one set of dogs only are engaged in succession, according to the rotation of the shaft and tappet-wheel, and consequently the tripping of the dogs takes place to prevent interlocking of the parts only.

From the foregoing description of the construction and operation of my improved cam device it will be noted that it provides for a quick intermittent reciprocating motion of the yoke-member and mechanism to which it is connected, as for instance in the operation of the slide-valve of an engine, and in this instance of course the operation of the cam is timed with respect to the operation of the slide-valve for operation of the engine, and of course the engine will be provided with the usual means for controlling its operation, including a governor. By providing the engine with this form of cam device, for a quicker movement of the slide-valve the inlet port and exhaust port are uncovered quickly for a more effective operation of the piston.

I claim:—

1. A cam device for imparting an intermittent reciprocating motion from a revolving shaft, comprising a wheel having a tappet projecting from its periphery and of less width than said periphery to provide a peripheral bearing surface at the side of the tappet, and a yoke-member having an elliptical-shaped recess therein to receive the wheel and bear against the periphery and aforesaid peripheral bearing surface with cavities in the yoke-member on a line with the transverse diameter of said recess through which the tappet passes, and means in said cavities for engagement of the tap-

pet to move the yoke-member alternately in opposite directions upon rotation of the wheel in either direction.

2. A cam device for imparting an intermittent reciprocating motion from a revolving shaft comprising a wheel having a tappet projecting from its periphery at the center thereof to provide peripheral bearing surfaces at opposite sides of said tappet, and a yoke-member having an elliptical-shaped recess therein to receive the wheel and bear against the periphery and aforesaid peripheral bearing surfaces with cavities in the opposite walls of the recess on a line with the transverse diameter of the latter, and means having a limited movement in said cavities for engagement of the tappet to move the yoke-member alternately in opposite directions upon rotation of the wheel in either direction.

3. A cam device for imparting an intermittent reciprocating motion from a revolving shaft comprising a wheel having a tappet projecting therefrom, a yoke member having an elliptical-shaped recess therein to receive the wheel upon which said yoke-member is mounted to have a reciprocating motion, and spring-actuated dogs in opposite walls of the recess at opposite sides of the transverse diameter of said recess for engagement of the tappet to move the yoke member in opposite directions.

4. A cam device for operating the slide-valve of an engine, comprising a wheel

mounted on a driven shaft and having a 35 single tappet projecting from the periphery thereof, a yoke member having an internal elliptical-shaped recess the narrower diameter of which is of approximately the same diameter as the diameter of the wheel on 40 which said yoke-member is mounted to have a reciprocating motion, cavities in the opposite walls of the recess in the yoke member to form spaced apart shoulders at opposite sides of the transverse diameter of said recess; whereby the rotation of the wheel causes the tappet to pass one of the shoulders and engage the companion shoulder on rotation of the wheel in either direction.

5. A cam device for operating the slide-valve of an engine to impart a quick movement thereto for the purposes set forth, comprising a wheel having a tappet projecting from the periphery thereof, a yoke member having an internal elliptical- 55 shaped recess by which it is mounted on the tappet-wheel to have a reciprocating motion thereon, cavities in the opposite walls of the recess in the yoke member on a line with the transverse diameter of said recess, and 60 spring-actuated pawls in said cavities at opposite sides of the transverse diameter of the recess, said pawls bearing against the ends of the cavities to provide rigid shoulders for engagement of the tappet when the 65 tappet-wheel is moved in either direction.

URBAN S. ALSRUHE.
